UNITED STATES PATENT OFFICE.

OTTO A. HOKANSON, OF WOODSTOCK, ILLINOIS, ASSIGNOR TO WOODSTOCK TYPE WRITER COMPANY, OF WOODSTOCK, ILLINOIS, A CORPORATION OF ILLINOIS.

VARIABLE LINE SPACER FOR TYPEWRITERS.

Application filed October 14, 1920. Serial No. 416,804.

To all whom it may concern:

Be it known that I, OTTO A. HOKANSON, a citizen of the United States, residing at Woodstock, in the county of McHenry and State of Illinois, have invented certain new and useful Improvements in Variable Line Spacers for Typewriters, of which the following is a specification.

This invention relates to the mechanism for rotating a typewriter platen for line spacing, including means for shifting the platen various amounts differing from the ordinary line spacing.

The invention has for its object the provision of mechanism of the class named, which shall be of improved construction and operation. It is exemplified in the combination and arrangement of parts shown in the accompanying drawings, and described in the following specification, and is more particularly pointed out in the appended claims.

In the drawings, Figure 1 is a longitudinal section of one form of device embodying the present invention.

Figure 2 is a transverse section on line 2-2 of Figure 1.

Figure 3 is a transverse section on line 3-3 of Figure 1.

Figure 4 is a view similar to Figure 1, showing a slightly modified form of the invention.

Figure 5 is a section on line 5-5 of Figure 4.

Figure 6 is a fragmentary detail of one of the parts; and,

Fig. 7 is an elevation looking from the right in Fig. 6.

Referring first to the form of invention shown in Figures 1, 2, 3, 6 and 7, the numeral 10 designates a typewriter platen fixedly mounted on a platen shaft 11, which is journaled in a platen carriage, a portion of which is shown at 12. The end of the shaft

11 protrudes through the bearing portion of the carriage 12, and is surrounded by a sleeve 13, which forms a bushing journaled in the carriage 12. The shaft 11 extends beyond the bushing 13, and the end of the shaft is provided with a stem 14 secured to the sleeve 13 by a set screw 15 and fastened to the end of the shaft 11 by a set screw 16, so that when the parts are assembled, the shaft 11, the sleeve 13 and the stem 14 are

fixedly secured together. A finger wheel 17 is molded or otherwise rigidly secured on the end of the stem 14. The platen shaft 11, as shown in Figures 6 and 7, is provided with a groove 18 milled in one side thereof, the walls of the groove being inclined outwardly toward the periphery of the shaft. 55 A rod 19 is seated in the groove 18 and extends through a central opening in the end of the stud 14. A knob 20 is fixed to the projecting end of the rod 19 by a set screw 21. The knob 20 is provided with a flange 60 22, which loosely fits the projecting end of the stem 14, and has a limited rotary movement relative to the stem. A screw 23 is threaded through the flange 22 and extends into a slot 24 in the stem 14, as shown in Figure 3. The 65 screw 23 limits the amount of movement of the knob 20 relative to the stem 14.

The inner end of the sleeve 13 is provided with a flanged disk 25 having opposite portions of the periphery thereof flattened to 70 form bearing surfaces 26 and 27. A disk 28 is journaled on the sleeve 13 adjacent the outer face of the flange 25, and is provided with a flanged ring 29, which surrounds the flanged disk 25, and lies adjacent the periphery thereof. A pair of oppositely disposed rollers 30 and 31 is interposed between the bearing surface 26, and the inner face of the ring 29. The rollers 30 and 31 are loosely journaled on pins 32 and 33, which are respectively carried by tumblers 34 and 35 pivoted to the inner face of the flange 25 by screws 36 and 37. A compression spring 38 is interposed between the tumblers 34 and 35 and normally presses the rollers 90 95 into the bites formed between the bearing surface 26 and the inner face of the flange 29. Similar rollers 39 and 40 are arranged to travel on the bearing surface 27, and are provided with tumblers 41 and 42, and a spring 43.

The sleeve 13 is provided with a projecting bearing 44 on which is pivoted a cam lever 45, having opposite ends thereof interposed between tail pieces 46 on the tumblers 34, 35, 41 and 42. The inner end of the rod 19 is provided with a right angle portion 47, which fits into a slot in the cam lever 45, so that rotation of the rod 19 about its axis will shift the lever 45 upon its pivotal bearing 44. A ratchet wheel 48 is rigidly fixed

on the disk 28, and may be provided with the usual operating pawls and detent for rotating the platen for line spacing.

In operation, the platen may be rotated 5 in the usual manner, either by the ratchet wheel 48 or by the finger wheel 17. If the ratchet wheel is actuated for rotating the platen its movement will be transmitted through the flange 29 and one pair of the 10 clutch rollers 30, 31, 39 and 40, to the disk 25, and hence to the platen, since the disk is fixedly secured to the platen shaft. The clutch rollers are continually held tightly between the bearing surfaces so that there is no 15 possibility of lost motion between the parts 25 and 28. If it is desired to rotate the platen by the finger wheel 17, this is accomplished in the usual manner, since the finger wheel is rigidly connected with the platen. The 20 rotation of the finger wheel 17 in either direction will carry the ratchet wheel 14 in unison with the platen through the action of the clutch rollers 30, 33, 39 and 40.

If it is desired at any time to rotate the 25 platen independently of the ratchet wheel 48 for adjusting the position of the paper, or other purpose, this may be done by merely rotating the knob 20 in the direction in which it is desired to move the platen. 30 When the knob 20 is turned, the rod 19 will transmit the rotary movement to the cam lever 45. Assuming that the rotation is in a counter-clockwise direction, as viewed in Figure 2, the cam lever 45 will be moved 35 into the broken line position shown in that figure. This movement will tilt the tumblers 34 and 41 into the position shown in broken lines, compressing the springs 38 and 43, and leaving the disk 25 free to move in 40 a counter-clockwise direction relative to the flange 29. The rollers 31 and 40 will not oppose such counter-clockwise movement, for the reason that such movement tends to 45 free these two rollers from holding engagement between their contact surfaces, as will be readily apparent. When the clutch rollers have thus been released, further rotation 50 of the knob 20 will cause the right angular portion 47 of the rod 19 to engage the face of the groove 18 in the platen shaft 11, and also the edge of the opening in the bearing 44, through which the rod projects, so that the platen shaft 11 will be turned with the 55 knob 20, and the platen may thus be shifted to the desired position. Rotation of the 60 knob 20 in the opposite direction will produce a similar result upon the clutch rollers 31 and 40, so that the platen may be rotated in either direction entirely independently of the ratchet wheel 48 by merely turning the 65 knob in the direction desired.

The slot 24 and set screw 23 provide limit stops for the movement of the knob 20 relative to the stem 14, so that in case the torsion on the rod 19 produces too great a

strain in the rod, the end of the set screw 23 will engage the edge of the slot 24, and thus assist the right angle portion 27 of the rod in the rotation of the platen.

If it is desired to remove the platen from 70 the carriage 12, this may be done by loosening the set screw 16, and sliding the platen shaft 11 endwise to the right, as viewed in Figure 1. This will withdraw the platen shaft from the sleeve 13 without disturbing the assembled relation of the operating mechanism. A cover plate 50 may be removably secured to the flange 29 to form a 75 housing for the clutch rollers and their operating parts.

The modification shown in Figures 4 and 5 is similar to the form already described, except that the finger wheel 52 for the ordinary rotation of the platen is secured to the stem 14 outside of the platen adjusting disk 53 85 instead of on the inner side of the adjusting knob, as shown in Figure 1. In the modified construction, a collar 54 to which the adjusting wheel 53 is secured, is journaled on the stem 14 and is provided with a stud screw 55, which closely fits an opening in the collar 54 and extends through a slot 56 in the stem. The inner end of the stud screw 55 is provided with a reduced threaded portion 57, which is threaded into a transverse opening 58 in the rod 19. This arrangement will hold the wheel 53 and the rod 19 for rotation in unison with one another without causing the rod or wheel to bind upon the stem 14. The rotation of the 90 wheel 53 will act in the same way as the rotation of the knob 20, to first release the clutch rollers and then rotate the platen independently of the ratchet wheel 48. The platen shaft in this case may be withdrawn 95 without disturbing the operating mechanism by releasing the set screw 16. A washer 59 may be interposed between the lever 45 and cover plate 50 to prevent sliding 100 of the lever on its bearing 44.

I claim:

1. The combination with a rotary platen, of a line spacing wheel loosely mounted thereon, a roller clutch for causing said wheel and platen to rotate in unison with one another, and means for rotating said platen having driving connection with said platen independent of said line spacing wheel and roller clutch, said means comprising a rotary member arranged to release said clutch during an initial rotation and to rotate said platen during a continuation of the rotation of said member subsequent to the release of said clutch.

2. The combination with a typewriter platen, of a line spacing wheel journaled for rotation relative thereto, said platen and wheel having oppositely arranged surfaces centrally separated and inclined toward one another at opposite sides of the 125

centrally separated portions, rollers interposed between said surfaces, yielding means for pressing said rollers away from one another into the bites formed by said surfaces to cause said platen and wheel to move together, and means arranged to rotate on the axis of said platen for releasing said rollers and rotating said platen independently of said line spacing wheel.

10 3. The combination with a typewriter
platen and a ratchet wheel mounted to ro-
tate relative thereto, of a roller for holding
said platen and ratchet to rotate in unison
with one another, a device arranged to rotate
15 upon the axis of said platen for releasing
said roller to permit rotation of said platen
independently of said ratchet and means
having a limited movement relative to said
platen for operating said device, said means
20 being arranged to rotate said platen when
actuated beyond its limited movement rela-
tive thereto.

4. The combination with a typewriter platen, of a line spacing wheel journaled for rotation relative thereto, oppositely disposed surfaces on said wheel and platen and inclined toward one another, a clutch roller interposed between said surfaces, an operating member for said roller a cam lever rotatable about the axis of said platen for releasing said roller and a rod arranged axially of said platen and having a limited rotary movement relative thereto for operating said cam lever.

35 5. The combination with a typewriter platen and a line spacing wheel journaled for rotation relative thereto, of clutch members secured to said platen and wheel and having oppositely disposed surfaces inclined
40 toward one another, a roller interposed between said surfaces, an operating member on which said roller is loosely journaled, a device pivoted for rotation about the axis of said platen for moving said operating
45 member to release said roller, and a single member for operating said pivoted device to release said roller and for rotating said platen when said roller has been released.

6. The combination with a typewriter
50 platen having a platen spindle, a line spacing
wheel journaled for rotation on said
spindle, roller clutch mechanism for securing
said wheel and platen for rotation in
unison with one another, a device rotatable
55 about the axis of said platen for releasing
said clutch mechanism, a rotary finger piece
having a lost motion connection with said
spindle independent of said roller clutch
and means having a limited movement rela-
60 tive to said platen spindle for causing said
finger piece to operate said releasing device
during an initial movement thereof.

7. The combination with a typewriter platen, a platen spindle, and a frame in which said platen is journaled, of a line

spacing wheel mounted on said spindle for rotation relative thereto, rotary clutch mechanism for causing said platen and wheel to rotate in unison with one another, means for releasing said clutch mechanism to permit independent rotation of said platen and wheel, and a sleeve journaled in said frame for supporting said clutch mechanism, and operating means independent of said platen spindle.

8. The combination with a typewriter platen, a platen spindle and a carriage in which said spindle is journaled for rotation, of a sleeve surrounding said spindle and journaled in said carriage, a line spacing wheel journaled on said sleeve, rotary clutch mechanism carried by said sleeve for holding said platen and wheel for rotation in unison with one another, operating means secured to said sleeve for rotating said platen, an axially arranged rod in said spindle having a limited rotary movement relative thereto for controlling said clutch mechanism, means supported by said sleeve for actuating said rod and means for releasably securing said spindle in said sleeve so that said platen and spindle may be removed from said carriage without disturbing the assembled relation of said clutch mechanism and its operating parts. 95

9. The combination with a typewriter platen and a spindle therefor, of a disk secured to said spindle and having a portion of the periphery thereof flattened to form a continuous bearing surface, a ring surrounding said disk and connected with said line spacing wheel, oppositely disposed clutch rollers interposed between said flat surface and the inner face of said ring, a spring for forcing said rollers into the bites formed by said surfaces, means for rotating said disk and spindle in unison with one another, and means for moving one of said rollers in the direction of rotation of said disk and spindle to free said disk from said line spacing wheel. 100 105 110

10. The combination with a platen and a spindle therefor, of a line spacing wheel journaled for rotation about the axis of said platen, a clutch disk secured to said spindle and having oppositely disposed segmental portions removed to provide bearing faces, a clutch ring surrounding said disk and connected with said line spacing wheel, oppositely disposed rollers positioned on each of said surfaces and arranged to engage the inner periphery of said ring to prevent relative movement of said platen and line spacing wheel, springs for forcing said rollers away from one another into engagement with the bearing surfaces of said disk and ring, and mechanism for releasing said rollers to permit rotation of said platen independently of said line spacing wheel. 115 120 125

11. The combination of a typewriter 130

4

platen and a spindle therefor, of a sleeve surrounding said spindle, a platen carriage in which said sleeve is journaled, a line spacing wheel mounted on said sleeve for rotation relative to said platen, a disk connected with said platen and having a flat peripheral portion thereon, a ring secured to said line spacing wheel and surrounding said disk, a pair of rollers interposed between 10 said disk and ring, tumblers pivoted on said disk and having operating pins loosely engaging said rollers, springs connected with said tumblers for forcing said rollers oppositely into engagement with the bearing 15 surfaces on said disk and ring, a lever pivoted to rotate about the axis of said spindle and arranged to engage said tumblers alternatively to release one or the other of said rollers, a device rigidly connected with 20 said platen for rotating said platen, and a second device having a limited movement relative to said first mentioned rotating device, said second device being arranged to

operate said lever to release one of said rollers and subsequently rotate said platen 25 independently of said line spacing wheel.

12. The combination with a typewriter platen, and a spindle therefor, of a line spacing wheel mounted to rotate relative to said platen, roller clutch mechanism for 30 holding said platen and line spacing wheel to rotate in unison with one another, a finger wheel connected with said spindle for rotating said platen and line spacing wheel while connected by said clutch member, a 35 second finger wheel having a limited rotation relative to said platen, mechanism operated by the initial rotation of said second finger wheel for releasing said clutch mechanism, and means for causing said platen to 40 rotate in unison with said finger wheel after said clutch mechanism has been released.

In testimony whereof I have signed my name to this specification on this 9th day of October, A. D. 1920.

OTTO A. HOKANSON.
